DICTATING MACHINE

Joseph M. Parriott, Westport, Conn., and Joseph A. Rinaldi, Palisades Park, N.J., assignors to Dictaphone Corporation, Bridgeport, Conn., a corporation of New York

Filed May 21, 1962, Ser. No. 70,215

Term of patent 14 years

(Cl. D26—14)

FIGURE 1 is a front perspective view of a dictating machine, showing our new design;

FIGURE 2 is a plan view, to an enlarged scale;

FIGURE 3 is a front elevational view, to an enlarged scale;

FIGURE 4 is a side elevational view, to an enlarged scale;

FIGURE 5 is a rear elevational view, to an enlarged scale; and

FIGURE 6 is an opposite side elevational view, to an enlarged scale.

We claim:

The ornamental design for a dictating machine, substantially as shown.
